UNITED STATES PATENT OFFICE

WILLIAM G. HAGMAIER, OF WEST ALLIS, AND ERNEST C. SHAW, OF MILWAUKEE, WISCONSIN, ASSIGNORS TO ALLIS-CHALMERS MANUFACTURING COMPANY, OF MILWAUKEE, WISCONSIN, A CORPORATION OF DELAWARE

DEFIBERIZING MACHINE

Application filed February 27, 1930. Serial No. 431,698.

The present invention relates to improvements in the construction of defiberizing machines of the general type wherein slabs or logs of fibrous material such as wood, are fed longitudinally of their grain in contact with a plurality of rapidly moving defiberizing points carried by a rotor revolving at high speed.

A general object of the invention is to provide an efficient defiberizing machine of relatively compact and durable construction, wherein the defiberizing points are conveniently renewable.

A more specific object of the invention is to provide improvements which are especially applicable to defiberizing machines of the type disclosed generally in Aicher & McMillan Patent 1,476,032, granted December 4, 1923. The present invention contemplates improvements in rotor structures for machines of the general type shown in this patent, wherein slabs or logs of the solid fibrous material are fed longitudinally of their grain in contact with the points of rapidly moving defiberizing needles pivotally associated with a rotor revolving at high speed. In accordance with the improvement, the needles are specially mounted and constructed so as to enhance their durability and to reduce the cost of construction, and the rotor is formed to effectively support the needles while permitting convenient application and removal of the individual needles.

Some of the novel features of U-shaped needle construction, disclosed but not specifically claimed herein, form the subject of a copending application filed by William G. Hagmaier on February 24, 1930, Serial No. 430,548.

A clear conception of an embodiment of the novel features of the present invention and of the mode of constructing and operating machines built in accordance therewith, may be had by referring to the drawing accompanying and forming a part of this specification in which like reference characters designate the same or similar parts in the several views.

Fig. 1 is a part sectional side elevation of a two-rotor defiberizing machine of the needle type, embodying the present invention.

Fig. 2 is an enlarged end view of a part of one of the improved rotors.

Fig. 3 is an enlarged fragmentary longitudinal section through the rotor shown in Fig. 2.

The improved defiberizing machine specifically illustrated in the drawing comprises in general a pair of rotors 2 each mounted upon a horizontal main shaft 3 and providing a support for a plurality of radiating U-shaped needles 4; and a carriage 7 for presenting slabs or logs 8 of fibrous material to the points of the needles 4 as the rotor 2 is revolved at high speed. The rotor supporting shafts 3 are mounted in bearings 11 movably supported upon a main frame 10, these bearings being vertically adjustable by means of jack screws 12 so as to vary the effective needle point lengths. Each of the rotors 2 is adapted to be revolved independently of the other and at relatively high speed, by means of an electric motor 14 cooperating with the corresponding rotor shaft 3, through a belt drive 13, and the rotors 2 are preferably revolved in opposite directions so that the effective points of the needles 4 of the two rotors, approach each other at the tops of the rotors.

The carriage 7 is provided with supporting wheels 16 coating with rails 17, and is reciprocable over a horizontal top plate 6 having elongated transverse openings through which the points of the needles 4 are movable to cooperate with the under sides of the logs 8 which are confined within the carriage 7 and which rest by gravity upon the top plate 6. The carriage 7 is movable between sets of buffers 23 by means of a connecting link 18 secured to a set of continuously movable endless chains 19 by a pivotal connection, the chains 19 being constantly driven by an electric motor 22 through a belt drive 21 and a speed reducing chain drive 20. The movement of the carriage 7 is relatively slow as compared to the peripheral speed of the rotors 2, the latter being operable at approximately the speed of the motors 14, and the former being operable at considerably slower speed than that of the motor 19, by virtue of the intervening speed reductions.

The rotors 2 are housed within a fiber collecting chamber 9 disposed beneath the top plate 6 and formed by transverse walls 24 connecting the opposite sides of the frame 10, and are adapted to deliver the fiber as produced, into the chamber 9 from which the fiber is discharged through a lower conduit 15 by suction produced with a fan or the like. Each of the rotors 2 is provided with a series of annular disks 5 preferably formed of rubber or other flexible material, the successive disks 5 being spaced apart by means of spacers 25 and having openings 26 therethrough located inwardly of the disk periphery. The openings 26 in alternate disks 5 are alined, but the openings 26 in adjacent disks are staggered as shown in Figs. 2 and 3. The U-shaped needles 4 are pivotally associated with the flexible disks 5 at the openings 25, and are adapted to swing freely in planes parallel to the disks and perpendicular to the axis of the shaft 5, while being resiliently restrained against side displacement by the peripheral portions of the disks 5 which extend a considerable distance away from the rotor axis and between the bifurcations or tines of the needles 4. The disks 5 and spacers 25 may be clamped together by means of clamping nuts 27 located at the ends of the rotor, and if desired, the disks 5 may be prevented from rotating relatively to each other by means of a dowel pin or a key, in an obvious manner.

During normal operation of the defiberizing machine, the rotors 2 are being rapidly revolved in opposite directions within the chamber 9 beneath the top plate 6, by means of the electric motors 14, and logs 8 disposed within the carriage 7 are being reciprocated longitudinally of their grain, over the transverse openings in the plate 6 by means of the carriage reciprocating mechanism. As the successive points of the needles 4 rake through the lower portions of the logs 8, they comb out the fiber and deliver same to the collecting chamber 9 and to the discharge pipe 15 from which the fiber is automatically removed by suction. When the needles 4 engage a relatively hard portion of a log 8, they may swing freely within the pivot openings 26 of the disks 5, so as to clear the hard portion. The needles 4 may even deflect laterally, that is, longitudinally of the rotor 2, by virtue of the flexibility of the disks 5, thus preventing breakage of the needles.

The rubber disks 5 are preferably reinforced with fabric or metal screening, so as to prevent the needles 4 from pulling out through the peripheral portions of the disks 5. Due to the lateral flexibility of the disks 5, the needles 4 may be readily inserted and removed from the openings 26 by merely bending the peripheral portions of the disks 5 so as to permit the U-shaped needles 4 to be applied to or removed from the openings

26. By staggering the openings 26 in the successive disks 5, the needles 4 supported by the successive disks will have greater freedom of swinging without interfering with the needles of adjacent disks, than would otherwise be possible, and the disks 5 may be disposed closely adjacent to each other so as to secure a maximum number of defiberizing points. The use of rubber, with its wear resisting qualities, also enhances the life of the rotor, and the outwardly projecting peripheral portions of the disks 5 located between the tines of each needle 4, will also aid in preventing interference of the needles supported by adjacent disks 5.

From the foregoing description it will be apparent that the present invention provides a relatively simple and durable needle structure and an effective mounting therefor which permits convenient application and removal of the needles 4. The mounting of the needles is such as to protect the same against injury and the entire structure may be manufactured at relatively low cost.

It should be understood that it is not desired to limit the invention to the exact details of construction and to the precise mode of operation of machines such as herein shown and described, for various modifications within the scope of the claims may occur to persons skilled in the art.

It is claimed and desired to secure by Letters Patent:

1. Apparatus for reducing fibrous bodies to a mass of separated fibrous particles, including a rotor comprising a plurality of spaced, resiliently flexible, disk-like supports disposed side by side with their general planes extending substantially perpendicular to the axis of said rotor, and a plurality of yieldable defiberizing elements carried by each of said supports.

2. Apparatus for reducing fibrous bodies to a mass of separated fibrous particles, including a rotor comprising a plurality of resiliently flexible rubber supports disposed side by side in the general direction of the axis of said rotor and a plurality of defiberizing needles pivotally associated with each of said supports.

3. In a defiberizer, a rotor comprising a plurality of resiliently flexible disks disposed side by side in the direction of the axis of said rotor, and a plurality of circumferentially spaced needles pivotally associated with each of said disks.

4. In a defiberizer, a rotor comprising a series of laterally deflectable sheet-like supports disposed in planes substantially perpendicular to the axis of said rotor, and a plurality of needles pivotally associated with each of said supports.

5. In a defiberizer, a rotor comprising a series of laterally spaced deflectable disks disposed in planes substantially perpendicular

- lar to the axis of said rotor, and an annular series of needles pivotally associated with each of said disks.
6. In a defiberizer, a rotor comprising a series of laterally spaced and deflectable disks, the openings of adjacent disks being staggered, and a needle pivotally associated with each of said openings.
7. In a defiberizer, a rotor comprising a series of laterally spaced disks having deflectable portions provided with openings therethrough a substantial distance inwardly of the disk peripheries, and a plurality of U-shaped needles pivotally associated with said openings.
8. In a defiberizer, a rotor comprising a series of disks having laterally deflectable peripheral portions provided with openings disposed a substantial distance inwardly of the disk peripheries, and a U-shaped needle pivotally associated with each of said openings and having points projecting outwardly beyond the adjacent disk periphery.
9. In a defiberizer, a rotor comprising a plurality of disks, and needles pivotally and detachably associated with said disks, said disks being laterally deflectable to permit removal of said needles therefrom.
10. In a defiberizer, a rotor comprising a plurality of annular rubber disks, and U-shaped needles pivotally and detachably associated with said disks, said disks being laterally deflectable to permit removal of said needles therefrom.
11. In a defiberizer, a rotor comprising a plurality of laterally spaced rubber disks, and a plurality of needles pivotally associated with each of said disks, each of said needles having a pair of points located on opposite sides of the supporting disk thereof.
12. In a defiberizer, a rotor comprising a plurality of disks disposed substantially perpendicular to the rotor axis, and needles pivotally supported by said disks and normally radiating from said axis, each of said needles having a pair of points lying in a plane extending longitudinally of the rotor located on opposite sides of the supporting disk thereof.
13. In a defiberizer, a rotor comprising a plurality of plates disposed alongside each other and extending away from the rotor axis substantially perpendicular thereto, said plates having openings therethrough from one axial side thereof to the other, and a U-shaped needle passing through and pivotally supported at each of said openings, said plates extending a considerable distance outwardly between the bifurcations of each of said needles, and the latter being freely swingable parallel to the plane of said plates.

In testimony whereof, the signatures of the inventors are affixed hereto.

WILLIAM G. HAGMAIER.
ERNEST C. SHAW.
